Primary Examiner — Thomas Johannes*Assistant Examiner* — Chelsea Sealey(74) *Attorney, Agent, or Firm* — Christie, Parker & Hale, LLP(57) **CLAIM**

The ornamental design for a phone retractor carrying case, as shown and described.

DESCRIPTION

FIG. 1 is a rear perspective view of a phone retractor carrying case showing our new design;

FIG. 2 is a front perspective view thereof;

FIG. 3 is a rear perspective view of a phone retractor carrying case, without the unclaimed holster portion;

FIG. 4 is a front perspective view thereof;

FIG. 5 is a an exploded back perspective view thereof;

FIG. 6 is an exploded front perspective view thereof;

FIG. 7 is a back view thereof;

FIG. 8 is a front view thereof;

FIG. 9 is a left side view thereof;

FIG. 10 is a right side view thereof;

FIG. 11 is a bottom view thereof; and,

FIG. 12 is a top view thereof.

The broken line portion of the figure drawings is included to show unclaimed subject matter only and forms no part of the claimed design.
